UNITED STATES PATENT OFFICE.

WILLIAM ROBERTSON, OF BUFFALO, NEW YORK.

DESIGN FOR A CORK-EXTRACTOR CASING.

SPECIFICATION forming part of Design No. 29,379, dated September 20, 1898.

Application filed April 15, 1897. Serial No. 632,323. Term of patent 7 years.

To all whom it may concern:

Be it known that I, WILLIAM ROBERTSON, of Buffalo, in the county of Erie and State of New York, have originated and invented a new and useful Design for a Casing for Cork-Extractors; and I do hereby declare that the following is a full, clear, and exact description thereof, reference being had to the accompanying drawings, forming a part of this specification.

This invention consists in a design for a cork-extractor or cork-puller, which will be fully hereinafter described and claimed.

In the drawings, Figure 1 is a general view of my design for a cork-extractor. Fig. 2 is a section of the same, taken through the line X X of Fig. 1.

As shown in the drawings, the leading or material feature of my design consists of a fish ornamented upon the surface of the cyl-

inder 2, the ends of the cylinder 2 being stamped so as to represent a scaly or scalloped surface. The space 3, diametrically opposite the representation of the fish, is left plain, and these sections of the cylinder are separated by the elongated slots 4, cut diametrically opposite to each other.

Having described my invention, what I claim as new, and desire to secure by Letters Patent, is—

The design for a cork-extractor casing as herein shown and described.

In testimony whereof I have signed my name to this specification in the presence of two subscribing witnesses.

WILLIAM ROBERTSON.

In presence of—

O. E. HODDICK,
R. P. WIGHTMAN.
